[57] ABSTRACT

An artificial flower comprising an elongated semi-rigid stem configured to support a plurality of leaf-shaped elements and a flower-shaped element together above a supporting surface. The semi-rigid stem comprises a hollow tubular sleeve having a plurality of thin elongated members extending therethrough. The flower-shaped element includes an aperture through which the upper portion of the thin elongated members are passed to engage a securing means disposed to secure the flower-shaped element to the upper extremity of the hollow tubular sleeve. The lower portion of the elongated members extend outwardly from the hollow tubular sleeve and substantially at right angles thereto to form a base to support the entire artificial flower. The hollow tubular sleeve also includes a plurality of apertures configured to engage the leaf-shaped members.

DECORATIVE FLOWER

BACKGROUND OF THE INVENTION

1. Field of the Invention

An artificial flower comprising a flower-shaped element and a plurality of leaf-shaped elements attached to an elongated semi-rigid stem.

2. Description of the Prior Art

Handicraft has always been a form of recreation and relaxation. The old, the infirm and the handicapped are encouraged to adopt some form of handicraft as a therapeutic means to improve and rehabilitate their manual dexterity. If gainful employment could also be offered, by reason of the high usefulness of the item, much interest would be gained. Most handicraft do not have such possibility and are mostly nick-nack items.

Particularly, with the increased leisure time available to people as a result of changing work patterns and increased retirement, numerous handicraft kits and devices have been developed. The assembly and arrangement of artificial flowers is among the more common type of such devices.

Such devices include artificial flowers comprising a plurality of petals cooperatively assembled by means of a plurality of threads. In addition, various artificial flowers and corsage arrangements requiring the device to be assembled by the stapling or curling of the wire elements about one another exist.

However, in each instance various staples, wires, glues and tools are required. Thus, a need remains for an attractive, easy to assemble artificial flower which does not require additional tools and the like.

SUMMARY OF THE INVENTION

The present invention relates to an artificial flower of the type assembled from handicraft kits. As previously discussed, innumerable attempts have been made to create attractive and appealing artificial flowers.

The present invention combines a unique combination of elements specifically configured to produce an attractive artificial flower in easy to assemble kit form. To accomplish this, the present invention includes an elongated semi-rigid stem comprising a hollow tubular sleeve having a plurality of elongated wire-like elements extending therethrough. A plurality of apertures are formed along the length of the sleeve to engage a plurality of leaf-shaped elements as more fully described hereinafter. Each leaf-shaped element includes a body member and attachment means comprising a tab angularly oriented relative to the longitudinal axis of the body member. The upper and lower portions of the wire-like elements extend outwardly from the tubular sleeve to form an attachment means and base means respectively.

A flower-shaped element including a centrally disposed aperture formed therein is affixed to the upper portion of the elongated wire-like elements by a circular securing means including a centrally disposed aperture formed therein.

To assemble, the upper portions of the wire-like elements are passed through the aperture of the flower-shaped element and aperture of the circular securing means. The upper portions of the elongated wire elements are then bent to a position substantially perpendicular to the sleeve to engage the circular securing means. This serves to secure the flower-shaped element adjacent to the upper portion of the tubular sleeve. The

individual leaf-shaped elements are then attached to the stem by passing the tabs through the apertures formed on the tubular sleeve. To further secure the leaf-shaped elements to the stem, the leaf-shaped elements may be twisted. The lower portion of the wire-like elements are passed through a base and bent to a position substantially perpendicular to the tubular sleeve to engage the base to support the artificial flower upright.

By the combination of these unique elements, the present invention relates to a new and novel artificial flower.

The invention accordingly comprises the features of construction, combination of elements and arrangement of parts which will be exemplified in the construction hereinafter set forth, and the scope of the invention will be indicated in the claims.

BRIEF DESCRIPTION OF THE DRAWINGS

For a fuller understanding of the nature and objects of the invention, reference should be made to the following detailed description taken in connection with the accompanying drawings in which:

FIG. 1 is a front view of an artificial flower.

FIG. 2 is a partial detailed rear view of a stem and flower-shaped element.

FIG. 3 is a partial cross-sectional view of a stem and leaf-shaped element.

FIG. 4 is an exploded view of an artificial flower.

Similar reference characters refer to similar parts throughout the several views of the drawings.

DETAILED DESCRIPTION OF THE PREFERRED EMBODIMENT

As shown in FIG. 1, the present invention generally indicated as 10 comprises an artificial flower including a semi-rigid stem 12, a plurality of leaf-shaped elements 14, flower-shaped elements 16 and securing means 18.

As best seen in FIGS. 3 and 4, semi-rigid stem 12 comprises a hollow tubular sleeve 20 having a plurality of thin elongated wire-like elements 22 extending therethrough. The upper portion 24 of elements 22 extend outwardly from the upper portion 26 of sleeve 20 which cooperate with the upper edge 28 of sleeve 20 to form a first fastener means as more fully described hereinafter. The lower portion 30 of elements 22 extend outwardly from the lower portion 32 of sleeve 20 to form a second fastener means 34 (FIG. 1). In addition, a first attachment means comprising a plurality of apertures 36 is formed along the length of hollow tubular sleeve 20 to anchor leaf-shaped elements 14.

Each leaf-shaped element 14 comprises body member 38 and second attachment means 40 comprising a tab which may be angularly oriented relative to the longitudinal axis of body member 38 such that when assembled leaf-shaped elements 14 extend upwardly on a diagonal relative to stem 12.

Flower-shaped element 16 comprises body 42 having centrally disposed aperture 44 formed therein and a plurality of petal-like members 46 formed about the periphery of body 42. Securing means 18 comprises a substantially flat circular element 48 having a centrally disposed aperture 50 formed therein.

The artificial flower 10 is specifically configured for ease of assembly in kit form without the necessity of tools or other paraphernalia. As described hereinafter,

a plurality of such flowers 10 may be combined in an attractive arrangement.

To assemble, the upper portions 24 of elements 22 are passed through aperture 44 of flower-shaped element 16 and aperture 50 of securing means 18. The diameter of aperture 44 relative to sleeve 20 is such that the bottom surface 52 of flower-shaped element 16 engages upper edge 28. Elements 22 are then bent downward substantially parallel to body 42 and flat circular element 48 to secure flower-shaped element 16 between element 48 and upper edge 28.

Each leaf-shaped element 14 is then attached to stem 12 by passing tab 40 through an aperture 36. To further secure the leaf-shaped element 14 thereto, they may be twisted about stem 12 in the manner shown.

A plurality of assembled flowers 10 may then be arranged together in a planter or similar arrangement (not shown). To support the individual flowers 10 in a substantially upright position relative to the supporting surface, the lower portion 30 of elements 22 are disposed substantially perpendicular to sleeve 20 to form the second fastener means 34. The lower portion 30 of elements 22 may be passed through a base 54 (FIG. 4) and bent as previously described to secure stem 12 to base 54.

It will thus be seen that the objects set forth above among those made apparent from the preceding description, are efficiently attained, and since certain changes may be made in the above construction without departing from the scope of the invention, it is intended that all matter contained in the above description or shown in the accompanying drawing shall be interpreted as illustrative and not in a limiting sense.

It is also to be understood that the following claims are intended to cover all the generic and specific features herein described, and all statements of the scope of the invention which, as a matter of language, might be said to fall therebetween.

Now that the invention has been described,

What is claimed is:

1. An artificial flower comprising: stem means including a first attachment means, leaf means including

a second attachment means, said first attachment means comprising aperture means formed in said stem means, said second attachment means comprising tab means integrally attached to said leaf means and formed from a flexible material, said tab means positioned within said aperture means and wrapped about at least a portion of the outer peripheral surface of said stem means, whereby said leaf is secured to said stem means; flower means connected to said stem means, a first fastener means interconnected between said stem means and said flower means.

2. An artificial flower as in claim 1 wherein said stem means comprises a hollow tubular sleeve and a plurality of elongated elements extending through said sleeve, said first fastener means comprising a first end portion of said plurality of elongated elements extending out of one end of said sleeve, said plurality of first end portion elements disposed substantially radially of said flower means and into engagement with said flower means, whereby said flower means is connected to said stem means.

3. An artificial flower as in claim 2 further comprising a second fastener means at least partially defined by a second end portion of said plurality of elongated elements, base means connected to said stem means by said second end portion of elements, said second end portion of elements disposed substantially radially from the longitudinal axis of said stem means and in engagement with said base means.

4. The artificial flower of claim 1 further including securing means to secure said flower means to said stem means, said securing means comprising a substantially flat element mounted on said flower means having an aperture formed therein, said upper portion of said elongated elements extending through said aperture of said substantially flat element, whereby said flower means is secured to said stem means.

5. The artificial flower of claim 1 wherein said tab means is angularly oriented to said leaf element such that said leaf element is inclined relative to said stem.
